MESNE ASSIGNMENTS, TO THE ALLEN-SHERMAN-HOFF COMPANY, OF PHILADEL-
PHIA, PENNSYLVANIA, A CORPORATION OF PENNSYLVANIA

HOPPER CONSTRUCTION

Application filed July 27, 1925, Serial No. 46,503. Renewed August 29, 1929.

This invention relates to hopper construction and particularly to the construction of a liquid handling gate for a hopper containing solid and liquid materials.

One object of the invention is to construct a door frame, for a solid and liquid material containing hopper having a bottom discharge opening, which is formed to deliver into a stationary trough, or through the bottom opening of the hopper, substantially all the liquid passing through the hopper.

Another object is to construct a gate comprising a door frame and door for a liquid and solid material carrying hopper having a bottom discharge opening, which parts cooperate to form a plurality of separate, bottom fed liquid channels on one or more sides of the door.

Another object is to construct a liquid handling gate for a hopper having a bottom discharge opening having a self cleaning liquid carrying channel at the rear end thereof.

Another object is to construct a door frame for a hopper having a bottom discharge opening, which is provided with means for permitting drainage of water beneath the bottom ends of the hopper walls over the frame and for directing all water falling onto the frame, onto the door or stationary trough.

Other objects will appear and be pointed out hereinafter.

In the drawings accompanying and forming a part of this specification:

Fig. 1 is a vertical sectional view taken through one form of gate construction embodying my invention;

Fig. 2 is a longitudinal, vertical section taken substantially on line 2—2 of Fig. 1;

Fig. 3 is a top plan view taken on line 3—3 of Fig. 2;

Fig. 4 is a view similar to Fig. 1 but showing another form of gate construction embodying my invention;

Fig. 5 is a longitudinal, sectional view taken substantially on line 5—5 of Fig. 4; and

Fig. 6 is a top plan view of the apparatus

shown in Fig. 5 with members 31 and the parts thereon removed.

Referring first to Figs. 1, 2 and 3, it will be understood that 1 designates the fragmentary bottom end of the walls of a hopper having a bottom discharge opening 2. The gate shown in these figures includes a door frame 3, a door 4 and girders 5 attached to the frame and disposed on either side of the opening 2. These girders 5 are also connected to the hopper walls 1, by any suitable means, for example, by angles 6, 7 and 8 and extend along and beyond each opening 2 to carry suitable rollers 9 upon which the door 4 moves in a substantially horizontal plane.

The frame 3 consists of a plate-like portion 10 having substantially vertical upstanding marginal flanges 11 on opposite sides thereof, a corresponding marginal flange 12 at the rear end thereof and a vertical flange 13 at the front end thereof. The plate 10 constitutes a hollow square, the opening 14 through the center of which is substantially aligned with the opening 2 in the hopper so that material discharged from the hopper will pass through the opening 14. Adjacent to the inner edges of the plate 10, about the opening 14, are disposed depending flanges 15 on all four sides of the opening 14. The flange 15 at the rear end of the opening 14 is integral with a flange 16 which diverges from the flange 15 and extends downwardly to a point below the lower edge of the flanges 15, for a purpose later to be described. Openings 15^a in flanges 15 permit escape of liquid and smaller pieces of solids to the exterior thereof.

The door 4 is of substantially the construction described in my copending application, Serial No. 683,792, now Patent 1,547,284, patented July 28th, 1925 and comprises a body portion 17 suitably lined with refractory material and provided with marginal side flanges 18 and rear end flanges 19. At the front end of the door a horizontally disposed flange 20 projects forwardly to discharge liquid into a stationary trough 21 which extends across the line of movement of the door and is adjustably carried by the door frame, as by means of a bolt 22 adjustable in a slot 23 and

also by means of shims 24. By these means the trough 21 may be adjusted in a vertical plane, as well as in a horizontal plane. With the door 4 and frame 3 assembled in the operative position shown in these figures, the depending flanges 15 and 16 cooperate with the marginal door flange 19 to form a plurality of, in this case two, bottom fed liquid carrying channels designated by the letters *a* and *a'* on Fig. 2. It will be understood that a mixture of solid and liquid material accumulating on the door 4 and in the hopper will result in most of the water and some small amount of the ash or solid material passing into channel *a* where practically all of such solid material will be retained while some of the liquid may pass on into channel *a'*. The side flanges 15 cooperate with the side flanges 18 on the door in a similar manner but form only one liquid carrying channel on each side of the door, each of which communicates with the rear end channels *a* and *a'*. When the door 4 is moved into open position with respect to the door frame 3, the front end flange 20 of the door will assume substantially the position indicated in phantom in Fig. 2 beneath and in substantially the same vertical plane with flange 16 so that channel *a* is substantially self cleaning by gravity as regards not only its liquid but also its solid content. The projection of flange 16 laterally beyond the side flanges 15 provides means for removing an accumulation of solid material on the door between the flanges 15 and 18 as will readily be understood.

From the description of Figs. 4 and 5, which follows hereinafter, it will be understood that flanges similar to flange 16 may be formed with the side flanges 15 of the frame 3 to form two bottom fed liquid carrying channels similar to the channels *a* and *a'* shown by these figures as being only at one end of the door.

I have provided means for permitting passage of liquid from within the hopper to the outside of the ash retaining hopper walls and for drainage of liquid on the door frame to the door or stationary trough. The form of this means shown in Figs. 1 to 3 comprises a plurality of members which may be termed "stools" and which are cast metal pieces interposed in the space between the top of plate 3 and the bottom ends of the hopper walls 1. Each stool comprises a top horizontally disposed portion 25, a depending flange 26 at the inner edge thereof which extends to below the top of plate 10 and to within the opening 14 in frame 3, and is supported on the frame 3 by legs 27 extending from flange 26 and legs 27^a depending from portion 25. Each leg 27 preferably straddles a lug 28 on the frame 1. The lugs 28 are preferably not continuous but are separated by gaps 29 through which liquid may flow beneath the hopper walls 1

down along the flanges 15 onto the door 4. The walls 1 and flanges 26 act as ash retaining walls. The spaces 29^a between the flanges 26 and flanges 15 permit liquid to escape from the hopper onto the frame and thence pass to the door or trough 21 through openings 30 and 30^a when the liquid banks up in the hopper sufficiently. At the front end of the frame 3 openings 30 are provided for liquid accumulating beneath the walls 1 at that end of the frame, this opening 30 being disposed to discharge water onto the door 3 or into the trough 21, as desired. Other openings 30^a may be employed to discharge water onto the door 3.

Referring now to Figs. 4, 5 and 6, the gate shown in these figures includes a door frame 31, a door 32 and a stationary trough 33, the numeral 34 indicating fragmentarily the bottom ends of hopper walls between which a bottom discharge opening 35 is formed. The door 32 is similar in substantially all respects to the door 4 of Figs. 1, 2 and 3. The stationary trough 33 differs slightly in configuration from the corresponding stationary trough 21 of Figs. 1, 2 and 3, but is supported for vertical and lengthwise adjustment, by means of shims 34^a and bolts 35, in substantially the same manner as described for the trough 21 in Figs. 1 to 3.

The door frame 31 comprises a horizontally disposed plate 36 having upwardly and outwardly inclined flanges 37 at the outer periphery thereof on all four sides, the plate 36 being substantially rectangular and having a centrally disposed rectangular opening 38. The frame 31 is connected to the hopper walls 34 and carries the oppositely disposed door carrying girders 39. Adjacent to the inner edges of the plate 36 are depending flanges 40 on each side of the opening 38, which it will be noted registers with the opening 35 between the hopper walls. These flanges 40 are preferably, although not necessarily, provided with openings 41 which extend from the bottom edge of the flange upwardly to permit ready escape of liquid and of smaller particles of solid material from the hopper. Outer flanges 42 likewise depend from plate 36 and are spaced outwardly from the depending flanges 40 and preferably extend to a point below the lower edges of the flanges 40. As shown in these figures, the flanges 42 extend on the rear end and both sides of the frame 31 and cooperate with the marginal rear end and side edges 43 and 44, respectively, of the door 32 to form a plurality of, in this case two, bottom fed liquid carrying channels *b* and *b'* at the rear end and both sides of the door 32. Liquid and finely divided solid material may pass into the channels *b* where most of the solid material will be retained while the liquid may flow into channels *b'* and be discharged at one end of the door. The horizontal flange

45 at the front end of the door 32 assumes substantially the position indicated in phantom in Fig. 5 below and in substantially the vertical plane of the rear depending 5 flange 42 so that in moving the door 32 in open position not only the side channels *b* but also the rear end channel *b* will be automatically self cleaning. The side channels *b'* will discharge any solid material therein 10 onto the top of the body portion of the door 32, as the door moves to open position. When the door is being moved to closed position, the depending wall 42 will force such material on top of the door outwardly over the top 15 of the rear end flange 43. In this manner the channels are all substantially self cleaning every time the door is opened and closed.

The means provided in the apparatus of Figs. 4 to 6 for permitting drainage of liquid 20 over the door frame and beneath the bottom ends of the hopper walls consists of a series of vertical ribs 46 integral with the upper side of the plate 36. The ribs 46 cooperate with the plates 47 to form stools correspond- 25 ing to those above described. These ribs are separated by gaps 46^a through which liquid may flow below the walls 34 and carry on their top surfaces plates 47, which project inwardly beyond the flanges 40 and extend 30 down below the top of plate 36 to form ash retaining walls and liquid passages extending upwardly from within the ash retaining walls to outside thereof and on the top of the frame. At the front end of the frame 35 an opening 48 permits escape of liquid from the top of frame 31 into the stationary trough 33 by way of an adjustable deflector 49, which is carried by the frame while additional openings 50 in frame 31 may be em- 40 ployed to conduct liquid on to door 32.

Having thus described my invention so that those skilled in the art may be able to practice the same, what I desire to secure by Letters Patent is defined in what is 45 claimed.

What is claimed is:

1. In combination with a hopper for containing solid and liquid material and having an opening in its lower portion, a door frame 50 having an opening registering with that of the hopper, upwardly extending flanges upon said frame spaced outwardly from the bottom ends of the hopper walls, and spacing means between the frame and hopper walls 55 providing for liquid drainage under the hopper walls.

2. In combination with a hopper for containing solid and liquid material and having a discharge opening in its lower portion, a door frame having an opening registering 60 with that of the hopper and attached to the hopper, upstanding flanges on said frame spaced outwardly from the bottom ends of the hopper walls, stools on the frame engaging the bottom ends of the hopper walls for

spacing the frame and the walls apart vertically, the stools having inner edge flanges extending below the top of the frame within the opening thereof.

3. In combination with a hopper for containing solid and liquid material and having a discharge opening in its lower portion, a door frame connected to the hopper and having an opening registering with the opening therein, inner flanges depending from the frame along the rear end and longitudinal sides of the opening, outer flanges depending from the frame outwardly from the said inner end and side flanges, a movable door constituting a closure for the opening, the door 75 having upstanding flanges along its rear end and two sides spaced outwardly from said outer depending frame flanges and extending above the bottom thereof to form therewith a plurality of bottom fed liquid carrying 80 channels along the rear end and sides of the door, the door moving sufficiently when opened to clear the space between the inner and outer frame flanges.

4. In combination with a hopper for containing solid and liquid material and having a discharge opening in its lower portion, a door frame connected to the hopper and having an opening registering with the discharge opening thereof, inner flanges depending 85 from the inner periphery of the frame about the opening and provided with notches in their lower edges, an outer flange depending from the frame to the rear of the rear inner flange, a movable door constituting a closure 90 for the discharge opening and having upstanding flanges on the rear end and sides thereof spaced outwardly of said depending frame flanges and extending above the bottom edges of the depending flanges to form 95 therewith a plurality of bottom fed liquid carrying channels.

5. In combination with a hopper having a discharge opening in its lower portion, a door frame having an opening aligned therewith, 100 upstanding flanges on said frame spaced apart from and surrounding the lower ends of the walls of the hopper, means for spacing the frame and hopper whereby fluid passages are formed extending from within the 105 hopper to the space enclosed by said upstanding flanges, and drain means receiving fluid from said space.

6. In combination with a hopper for containing solid and liquid materials and having a discharge opening in its lower portion, a frame having an opening aligned with said discharge opening, a door for closing said opening, solid material retaining walls on the frame about the opening thereof, upstanding flanges surrounding the frame and spaced outwardly from the lower ends of the solid material retaining walls of the hopper, and forming main liquid carrying passages outside of said solid material retain- 120 125 130

ing walls of the hopper, the frame having auxiliary liquid carrying passages extending upwardly from said door to the main passages.

- 5 7. In combination with a hopper having a discharge opening in its lower portion and having solid material retaining hopper walls extending upwardly from said opening, a frame cooperating with the said walls having
10 a central opening aligned with said discharge opening, solid material retaining walls on the frame about the said central opening, up-
standing flanges on the frame spaced apart outwardly from the lower ends of said solid
15 material retaining walls of the hopper and forming main liquid carrying passages outside of the said solid material retaining walls, a door serving as a closure for the opening in the frame and forming with the frame
20 auxiliary liquid carrying passages extending upwardly from said central opening to said main passages, the said frame also having passages leading from the main passages through the frame.

25 In testimony whereof I hereunto affix my signature this 8th day of July, 1925.

FRANK B. ALLEN.
